UNITED STATES PATENT OFFICE.

ALONZO M. MCGAUGHEY, OF RUSSELLVILLE, INDIANA.

DISPLAY-RACK.

1,019,983.

Specification of Letters Patent. Patented Mar. 12, 1912.

Application filed April 24, 1911. Serial No. 623,110.

To all whom it may concern:

Be it known that I, ALONZO M. MCGAUGHEY, a citizen of the United States, residing at Russellville, in the county of

5 Putnam and State of Indiana, have invented certain new and useful Improvement in Display-Racks; and I do declare the following to be a full, clear, and exact description of the invention, such as will 10 enable others skilled in the art to which it appertains to make and use the same.

This invention relates to improvements in display racks for mattresses.

One object of the invention is to provide 15 a display rack of this character having an improved construction and arrangement of mattress holding trays and means whereby said trays are slidably supported to permit the same and the mattress thereon to be 20 drawn out from between other mattresses on the rack, thus bringing the desired mattress in position for advantageously displaying the same.

Another object is to provide a display 25 rack which will be simple, strong and durable in construction, and efficient in operation and which may be built in various sizes to hold any desired number of mattresses.

30 With these and other objects in view the invention consists of certain novel features of construction, combination and arrangement of parts as will be more fully described and particularly pointed out in the 35 appended claims.

In the accompanying drawings: Figure 1 is a side view of my improved rack; Fig. 2 is a vertical transverse section on the line 2—2 of Fig. 1 showing one of the sides in 40 position for displaying a mattress; Fig. 3 is a horizontal section on the line 3—3 of Fig. 2; Fig. 4 is an enlarged side view partly in section of a portion of one of the supporting posts or standards and one of 45 the supporting rollers and adjacent end of the rack frame engaged therewith; and, Fig. 5 is a vertical sectional view on the line 5—5 of Fig. 4.

In this embodiment of the invention I 50 provide a main supporting frame 1 comprising pairs of vertically disposed end posts or standards 2, the lower ends of which are secured to the end cross bars 3 of a base frame, said end bars 3 being connected near their ends by longitudinal side bars 4 as shown. The upper ends of the

standards or posts 2 are connected to a top frame comprising end bars 5 and longitudinal side bars 6.

Arranged at intervals on the inner sides 60 of the posts or standards 2 and in line with each other are series of rack supporting rollers 7, said rollers being revolvably secured to the posts by means of screws 8. The rollers 7 are preferably provided on 65 their inner ends with annular flanges 9 and short bosses 10, said bosses engaging the sides of the posts or standards and thus reducing the friction between the ends of the rollers and the standards. Any number 70 of rollers may be provided and the same are spaced apart to permit a mattress to rest on the racks engaged therewith.

Slidably engaged with the rollers 7 are 75 mattress supporting racks comprising rectangular oblong frames 11 the sides and ends of which are formed of channel iron bars preferably braced by diagonally arranged pairs of brace bars 12 and 13. The bars 12 are preferably of greater length 80 than the bars 13 and the bars of each pair are preferably arranged parallel with each other as shown, thereby forming a support for the mattress placed thereon. In arranging the rack frames 11 in the main frame 1 the 85 channel iron end bars of the rack frames are engaged with the corresponding pairs of rollers on the opposite end of the main frame and are thus slidably supported and adapted to be pulled or pushed laterally in 90 either direction from the frame and to a sufficient extent for displaying the mattress contained thereon. In order to limit the outward movement of the frame and thus prevent the same from being drawn out of 95 engagement with the rollers when pulled or pushed from either side of the main frame, I provide stop pins 14 which are inserted through the upper and lower sides of the channel iron ends of the rack frames 100 adjacent to the side bars thereof or at any position where it is desired to stop the movement of the rack frame. By thus arranging the stop pins 14 the latter will be brought into engagement with the rollers 105 when the rack frame has been drawn to the desired position for displaying the mattress.

In order to steady the mattress holding frames and to relieve the rollers of part of the strain occurring to the rack frames 110 when they are drawn out to display a mattress thereon, I preferably provide a series

of stop plates 15 which are pivotally connected to the inner sides of the standards in position to engage the upper sides of the ends of the rack frames as shown. The stop pins 15 are pivotally connected to the inner sides of the standards adjacent to the upper edges thereof and on the outer edges of the plates are formed right angular flanges 16 which engage the outer edges of the standards 2 and thus prevent the stop plates from swinging inwardly.

In using the racks the rack frame containing the mattress it is desired to display is drawn laterally from one side of the main frame to the limit of the movement of the rack frame after which the frames containing the mattress for a suitable distance above the displayed mattress are pushed back in the main frame to the limit of their movement in the opposite direction thus exposing the greater part of the displayed mattress.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as defined in the appended claims.

Having thus described my invention, what I claim is:

1. A display rack of the character described, comprising a main supporting frame, series of supporting rollers revolvably mounted on said main supporting frame, a

series of rack frames slidably engaged with said rollers and adapted to be shifted laterally in either direction from the sides of said main frame, means to limit the lateral sliding movement of said rack frames, and means to relieve the rollers of strain when said rack frames are shifted laterally to display the goods thereon.

2. In a display rack, a main supporting frame comprising pairs of vertically disposed end standards connected at their lower end to a base frame and at their upper ends with a top frame, a series of flanged rollers revolvably mounted on the inner sides of said standards, rack frames slidably engaged with said rollers, said rack frames comprising channel iron side and end bars, said channel iron end bars having a sliding engagement with said rollers whereby said rack frames are adapted to be shifted laterally in either direction in said main frame, stop pins adapted to be engaged with said end bars of the rack frames thereby limiting the lateral shifting movement of said frames in either direction, stop plates pivotally connected to the standards of said main frame and adapted to engage the upper edges of the end bars of the rack frames, stop flanges formed on said plates, and diagonally arranged brace bars arranged between the end and side bars of said rack frames.

In testimony whereof I have hereunto set my hand in presence of two subscribing witnesses.

ALONZO M. MCGAUGHEY.
